UNITED STATES PATENT OFFICE.

CHARLES W. FLESCH AND WILLIAM J. SCHMITT, OF ROCHESTER, NEW YORK.

ROOF CONNECTION.

Application filed February 15, 1926. Serial No. 38,429.

To all whom it may concern:

Be it known that we, CHARLES W. FLESCH and WILLIAM J. SCHMITT, both citizens of the United States, and residents of Rochester, in the county of Monroe and State of New York, have invented certain new and useful Improvements in Roof Connections, of which the following is a specification.

The present invention relates to roof connections and more particularly to the type employed for draining a roof. An object of this invention is to provide a construction which will permit the roof engaging flange, the article obstructing rib, a seat for the strainer and the down-spout connection to be formed economically from one piece of material.

To this and other ends, the invention consists of certain parts and combinations of parts, all of which will be hereinafter described: the novel features being pointed out in the appended claim.

In the drawings:

Fig. 1 is a plan view of the connection with part of the strainer broken away;

Fig. 2 is a reduced section on the line 2--2, Fig. 1, showing the connection mounted upon a roof; and

Fig. 3 is an enlarged sectional view showing the manner in which the strainer is held against movement on its seat by the article obstructing rib.

Referring more particularly to the illustrated embodiment of the invention, 1 indicates a roof and 2 the down-spout. The down-spout connection 3 is, in this instance, formed from sheet material in the shape of a funnel having a reduced end 4 for connection with the down-spout 2. At the upper end of the funnel shaped portion 3 an outwardly presented portion 5 is provided which is formed in one piece with the portion 3 and acts as a seat for the strainer 6 which, in this instance, is in the form of an inverted cup-shaped member provided with openings 7, the edge of this strainer being rolled to provide a bead. Projecting upwardly from the seat 5 and in one piece with the latter is an abutment 9, the inner surface

of which is substantially equal in diameter 50 to the diameter of the margin of the strainer so that the strainer abuts this portion 9 and is held against movement in the plane of the seat 5. Extending downwardly and outwardly from the portion 9 is a portion 10 55 which acts as an article obstructing surface to prevent gravel or other articles rolling into contact with the strainer 7 or collecting about the strainer to pass through the openings thereof. Beyond the article obstructing surface 10 an outwardly presented flange 11 is provided which serves to rest upon the roof and support the connection 3.

It will thus be seen that the down-spout connecting portion 3, the seat 5 for the strainer, the strainer abutment 9, the article obstruction portion 10 and the supporting flange 11 may all be formed from one piece of sheet material. The rib formed by the portions 9 and 10 has the double function 70 of acting as a deflector for articles, and as an abutment for confining the strainer on the seat 1. This arrangement makes it unnecessary to provide any securing means for the strainer which may also be readily 75 formed of sheet material without any expensive operations.

What we claim as our invention and desire to secure by Letters Patent is:

A roof connection comprising a down-spout connecting portion, an outwardly presented portion at the upper end of the down-spout connecting portion forming a seat for a strainer, an upwardly extending portion forming an abutment for a strainer, a downwardly and outwardly extending portion leading directly from the upper edge of the abutment and forming an article obstructing surface and an outwardly extending portion leading directly from said article 80 obstructing surface and forming a support for the connection, and a strainer resting on the seat and having its edge in abutment with the upwardly extending abutment about the seat.

CHAS. W. FLESCH.
WILLIAM J. SCHMITT.
